UNITED STATES PATENT OFFICE.

RUDOLF M. OSTERMANN, OF EVANSTON, ILLINOIS, ASSIGNOR TO THE SUPERHEATER COMPANY, OF NEW YORK, N. Y., A CORPORATION OF DELAWARE.

SUPERHEATER FOR BOILERS.

Application filed June 28, 1924. Serial No. 722,890.

My invention relates to superheater arrangements for boilers, and has for its object to provide an improved structure for the better utilization of the heat of the combustion gases, both by convection and radiation, for the superheating of the steam generated in the boiler. According to my present invention, superheater elements or tubes are placed at the hottest portion of the boiler, yet clear of the path of the combustion gases, so that these superheater elements will be heated chiefly, if not exclusively, by radiation. Another feature of the invention relates to protecting the boiler tubes against injury by the hot gases, the latter being led through a path which brings them in contact with one portion of each of the boiler tubes, and subsequently with other portions of said tubes. Additional features and advantages of this invention will appear from the detailed description following herein-after.

A typical example of my invention is illustrated in the accompanying drawing, in which Fig. 1 is a vertical section through a boiler provided with a superheater arrangement embodying the present improvements, and Fig. 2 is a section on line 2—2 of Fig. 1.

At 1 and 2 I have indicated the front and the rear wall respectively of the combustion chamber 3, and above them the headers 4, connected by the inclined tubes 6, and a drum 7 communicating with said headers by pipes 8 and 9 respectively. These parts may be of well-known construction.

An upright transverse baffle 10 extends from the lowermost tubes 6 to the uppermost ones, and from this baffle an inclined baffle 11 extends longitudinally of the tubes 6 forwardly to the header 4, above the lowermost row of tubes 6. In the pocket formed by these two baffles and the header 4 between the two lower rows of tubes 6, are disposed transverse superheater tubes 12 connected with headers 13 and 14 respectively one of which, 13 is adapted to deliver superheated steam to the engine (not shown), while the other, 14, receives steam, through a pipe 15, from the outlet header 16 of a superheater 17 located in the space between the drum 7 and the uppermost tubes 6. The inlet header 18 of the superheater 17 is connected with the steam space of the drum 7 by a pipe 19. From a point adjacent to

the outlet header 16 a transverse baffle 20 extends downwardly between the front header 4 and the baffle 10 and terminates short of the longitudinal baffle 11. An inclined transverse baffle 21 extends upwardly from the upper end of the baffle 20. These various baffles, in conjunction with the walls 22, 23, of the boiler setting, provide a sinuous path for the combustion gases from the chamber 3 to the outlet or stack connection 24. This path comprises an ascending portion 25 located at the upper portions of all the inclined tubes 6 and preferably, as shown, this ascending portion is constructed upwardly to obtain an approximately constant velocity of flow notwithstanding the reduction in the volume of the gases which results from their gradual cooling. The gases then travel forwardly in the path portion 26, along the tubes of the superheater 17, to thereupon pass downward, across the central portions of the upper tubes 6 in the descending path portion 27. The next path portion 28 leads the hot gases lengthwise of the forward portions of the lower tubes 6 (except those of the lowermost row), forwardly and downwardly above the inclined longitudinal baffle 11. Finally, the gases again pass upwardly in the ascending path portion 29 which is located forwardly of the transverse baffles 20 and 21, so as to heat the forward or lowermost portions of the upper tubes 6.

It will be noted that the superheater tubes 12 are located to one side of the above described path of the combustion gases. These tubes therefore receive but little heat from said gases by direct contact or convection, but are heated chiefly by radiation. It will also be observed that those portions of the tubes 6 which lie in the portions 27, 28, and 29 of the path of the combustion gases are shielded, by the baffles 10, 11 and by the superheater tubes 12, from the direct action of the hottest gases. The utilization of the heat of the gases is very efficient, both with respect to the boiler tubes 6 and the superheater tubes 12 and 17. The hottest gases are brought into heat exchange relation with the hot water at the upper end of the inclined tubes 6.

Various modifications may be made without departing from the nature of my invention as set forth in the appended claims.

I claim:

1. In combination with a boiler furnace and a boiler having inclined tubes set above said furnace at different levels, an upright baffle extending upwardly across said tubes, a longitudinal baffle extending from the first-mentioned baffle above the bottom thereof forwardly and downwardly at an inclination corresponding to that of said tubes and forming with said longitudinal baffle a closed pocket out of the path of the furnace gases but exposed to the radiant heat from said furnace, and a superheater located in the pocket below said inclined baffle and in advance of said upright baffle.
2. In combination with a boiler furnace and a boiler having inclined tubes set above said furnace at different levels, an upright baffle extending upwardly across said tubes, a longitudinal baffle extending from the first-mentioned baffle above the bottom thereof forwardly and downwardly at an inclination corresponding to that of said tubes and forming with said longitudinal baffle a closed pocket out of the path of the furnace gases but exposed to the radiant heat from said furnace, a depending baffle extending across the upper portions of said tubes above, and to within a distance from, said inclined baffle, means for forming a path connecting the upper ends of the upright channels at each side of said upright baffle, a superheater located in said connecting path, and another superheater, connected with the first-mentioned superheater, and located in the pocket below said inclined baffle and in advance of said upright baffle.
3. In combination with a boiler furnace and a boiler having tubes set above said furnace at different levels, an upright baffle extending upwardly across said tubes, a longitudinal baffle extending from first-mentioned baffle forwardly at a point above the lower end of said upright baffle, to form below said longitudinal baffle a pocket located to one side of the path of the hot gases, and a superheater located in such pocket.
4. In combination with a boiler furnace and a boiler having tubes, a baffle extending across said tubes between said tubes and said furnace and means to compel the gases from the furnace to pass directly only on the side of said baffle farthest from the furnace, and a superheater located on the other side of said baffle.

In testimony whereof I have hereunto set my hand.

RUDOLF M. OSTERMANN.
